UNITED STATES PATENT OFFICE.

HERBERT C. COOK, OF SPRINGFIELD, MASSACHUSETTS.

BALLOTTING DEVICE.

1,056,502.

Specification of Letters Patent. Patented Mar. 18, 1913.

Application filed July 11, 1910. Serial No. 571,445.

To all whom it may concern:

Be it known that I, HERBERT C. COOK, a citizen of the United States of America, and resident of Springfield, in the county of 5 Hampden and State of Massachusetts, have invented certain new and useful Improvements in Ballotting Devices, of which the following is a full, clear, and exact description.

This invention relates to improvements 10 in ballotting devices of a kind especially adapted for secret ballotting in lodges, societies and clubs; and it has for its object to provide a ballotting device which is particularly advantageous for its stated purpose by 15 reason of the construction or formation of the parts and the combination or arrangement thereof.

The ballotting device is illustrated in the 20 accompanying drawings, is described in conjunction therewith, and is set forth in the claims.

In the drawings:—Figure 1 is a side elevation of the device; Fig. 2 is a plan view 25 on a larger scale; Fig. 3 is a vertical sectional view as taken on the line 3—3, Fig. 2; Fig. 4 is a vertical sectional view taken from end to end through the drawer for the reception of the ballotting balls.

Similar characters of reference indicate 30 corresponding parts in all of the views.

The ballotting device includes a casing A having a substantially horizontal partition B dividing it into upper and lower compartments a, b, and the said casing has an opening d at its front which leads to the lower compartment b. The partition B has a hole f therethrough at a location near, and centrally relatively to, the said opening d, 35 which hole is surrounded by an upstanding tube D which advantageously is made with a flaring mouth; and the middle portion of the said partition B is made concave whereby the balls x for ballotting will be naturally 40 grouped or nested within the middle portion of the false bottom of the casing conducting to convenience in ballotting. The partition B is preferably surfaced at its upper side with a covering of cloth or other sound deadening material.

G represents a drawer to be entered into the lower compartment through the aforesaid opening d and to be practically wholly inclosed within the casing but capable of 45 being fully drawn out and away from the casing by the handle knob g. The said

drawer has a closing means for its top which in the present instance is represented by a horizontal wall h closing the forward end portion of the drawer and the hinge connected and movable cover i made with an ear or extension j at the rear end for convenience in upwardly swinging the cover to open the drawer. Through the top wall section h is an aperture m to register with the 60 lower end of the aforesaid tube D.

E represents a cover hinged to the top of the casing and for closing the same when the ballotting device is not in use.

As regards minor characteristics and features it may be stated that the parts are principally composed of sheet metal, and the casing is supported on a standard or pedestal N; and the partition which divides the casing into upper and lower compartments in the manner of a false bottom may be separately formed from the casing proper from a circular piece of sheet metal and dropped to place onto an internal ledge o with which the upstanding wall of the casing is provided.

In order that the plate or horizontal partition wall will not become accidentally turned from its proper position so that the tube carried thereby will be out of registry 85 with the hole m in the top of the inserted drawer, a rib t is provided vertically in the casing wall with which the notch like recess u in the edge of the partition plate has a rotation preventing engagement. And in 90 order that the inserted drawer may not slide out from its place in the lower compartment, especially when the ballotting device may be carried by its supporting standard in other than an upright position a curved spring plate v extending approximately horizontally 95 from the rear wall of the casing forwardly exerts a tensioning and retaining effect upon the drawer, which latter is guided between parallel upstanding ribs w w arranged in opposition and extending rearwardly on the bottom of the casing from either side of the front opening d.

When the device is to be used in a lodge, 100 club, or elsewhere, for ballotting, the balls both black and white are all retained in the upper compartment of the casing, the cover of which is swung open, and the empty drawer is entered in the lower compartment, as represented in Fig. 3; the members one 105 after another will go up to the ballot box and take, each, one of the balls, black or

white, according to the desire of voting and drop it into the open mouth of the tube D, whereupon it will fall through the hole *m* in the closed top of the drawer into the latter. The closing cover for the drawer provides means for concealing the ballot balls during the time that the drawer is being conveyed from the balloting device to the officer whose duty it is to count the ballots.

10 I claim:—

1. A balloting device comprising a casing having a substantially horizontal partition dividing it into upper and lower compartments, said casing having an opening at its front leading to the lower compartment, there being a hole formed through said partition, said partition being located below the upper edge of the casing and being adapted 15 to support ballot balls, a drawer adapted to enter the lower compartment through the opening in the front of said casing, a fixed top portion for said drawer, an opening in said fixed top portion with which the opening in the partition registers when said drawer is inserted in the lower compartment, a cover member hingedly connected to said fixed top portion, adapted to cover the remainder of the drawer, said hinged 20 cover member having an overhanging angular portion at the inner end of the drawer and a friction member carried by the casing which rides over said angular portion and bears upon said hinged cover member when 25 the drawer is in its closed position.
2. A balloting device comprising a casing, an internal ledge carried by said casing, a partition having a concave central portion resting loosely upon said ledge, interengaging 30 means between said partition and the wall of the casing to prevent said partition

from turning with relation to said casing, there being an opening formed through said partition, an upstanding flaring tube, the lower end of which registers with the opening of the partition, a drawer adapted to be inserted through the opening formed in the front wall of the casing, and a top portion for said drawer, there being an opening formed through said top portion which registers with the opening formed in the partition.

3. A balloting device comprising a casing, an internal ledge carried by said casing, a partition having a concave central portion resting loosely upon said ledge, interengaging means between said partition and the wall of the casing to prevent said partition from turning with relation to said casing, there being an opening formed through said partition, an upstanding flaring tube, the lower end of which registers with the opening of the partition, a drawer adapted to be inserted through the opening formed in the front wall of the casing, a top portion for 55 said drawer, there being an opening formed through said top portion which registers with the opening formed in the partition, and a hinged cover member comprised in said top portion which has an overhanging 60 angular end and a yielding friction member secured to the wall of the casing and adapted to ride over said angular portion and rest upon said hinged cover member when 65 the drawer is closed.

75 Signed by me at Springfield, Mass., in presence of two subscribing witnesses.

HERBERT C. COOK.
